ELECTRIC HORN

Gustav Zeininger, Oberesslingen, and Ludwig Holm, Stuttgart, Germany, assignors to Robert Besch Aktiengesellschaft, Stuttgart, Germany

Application July 8, 1932, Serial No. 621,475
In Germany July 25, 1931

3 Claims. (Cl. 177—7)

The present invention relates to electric horns particularly for motor vehicles.

In a known electric horn the electromagnet is secured inside on the bottom of the casing by a nut 5 screwed on a bolt. The bolt is affixed to the core of the electromagnet and serves together with a nut at the same time for fastening the supporting bracket or holder externally on the bottom of the casing. This construction has the drawback that an alteration in the fastening of the bracket also affects the fastening of the electromagnet, which is undesirable in view of the air-gap between the core of the electromagnet and the armature secured to the diaphragm. In order to enable the bracket or holder to be secured independently of the electro-magnet on the bottom of the casing, according to the invention, the holder is fastened to a recess in the bottom of the casing. In this construction the electromagnet bridges over the recess which is of suitable depth and is fastened to the non-recessed part of the casing bottom in such a way that it is not affected by the fastening of the holder.

Two examples of construction of the invention are shown in the accompanying drawing, in which:—

Figure 1 is a partial longitudinal section and partial elevation of the first example, and

Figure 2 a partial longitudinal section and partial elevation of the second example.

The form shown in Figure 1 has a pot-shaped casing 1, with an electromagnet 2, the armature 3 of which is attached to a diaphragm 4. In the centre of the casing bottom is a recess 5, to which a bolt 6 and a washer 7 are riveted. The base-plate of the electro-magnet 2 bridges the recess 5, and is riveted in known manner to the flat part of the casing bottom.

On the outwardly extending bolt 6 two flat brackets or holders 9 are fastened by a nut 8 screwed on the free end of the bolt, which holders are spaced apart by two bushes 10 and 11. A screw-bolt 12 passes through the bush 11; on its free end is mounted a clip 13, which embraces a cross-rod 14 lying, for example, in front of the radiator of a motor-car and is secured by a nut 15.

The recess 5 is made so deep that the bolt 6 can be fastened to the bottom of the casing without impeding the installation of the electromagnet.

As can be seen from Figure 1, the rod 14 lies laterally close to the casing of the horn 1, and the fastening clip 13 is arranged on the side of the holder 9, 9 facing the casing 1. By this

construction a fastening for the horn which does not take up much room is produced.

The two flat holder plates 9, 9, ensure a springy suspension of the horn in such a way that the oscillations of the horn run parallel to the oscillations of the diaphragm 4, which is desirable for acoustic reasons.

In Figure 2 a construction is shown in which instead of the two springy holders 9, 9, a rigid holder 16 is fitted, which together with a rubber buffer 17 is fastened by the nut 8 on the bolt 6. On the free end of the bracket 16 an angle-piece 18 is arranged for fastening the horn to a supporting surface or the like.

In both examples, the horn can be turned about the axis of the bolt 6 on slackening the nut 8, so that the horn can be easily brought into the most favourable position required, for example, in order to obtain a convenient positioning of the cable terminals 19.

We declare, that what we claim is:

1. An electric horn comprising a casing having a recess in the bottom wall thereof, an electromagnet secured to the bottom wall of said casing and bridging said recess, an armature, a diaphragm connected to said armature, a bolt secured in the recess in said casing independently of said electromagnet, and at least one supporting plate secured to said bolt and extending parallel to said diaphragm to a position laterally outward of the body of the horn.

2. An electric horn comprising a casing having a recess in a wall thereof concentric with the longitudinal axis of said horn, an electromagnet secured to the bottom wall of said casing and bridging said recess, an armature, a diaphragm connected to said armature and a supporting member secured in the recess in said casing independently of said electromagnet and in a manner permitting a rotational body adjustment of said horn about its longitudinal axis on said supporting member.

3. An electric horn comprising a casing having a recess therein and an opening in the recess, an electromagnet secured to the bottom wall of said casing and bridging said recess, an armature, a diaphragm connected to said armature, a bolt passing through the opening in the recess in said casing, said bolt being independent of said electromagnet, a washer riveted on said bolt in contact with said casing and at least one supporting plate engaging about said bolt against said washer and extending parallel to said casing.
